COMBINATION STORM WINDOW

Joseph L. Metzger, Louisville, Ohio

Application June 26, 1944, Serial No. 542,044

4 Claims. (Cl. 160—182)

My present invention, in its broad aspect, has to do with combination storm windows and screens for attachment to the outside faces of ordinary window casings, and which have means for providing ventilation when desired, and also means whereby not only screens may be substituted for glass storm windows, and vice-versa, but one section of the window may be glassed and the other screened.

One of the principal advantages of my invention is that the frame of my combination storm window and screen is flat, and the removable glass and screen sashes therein lie flush with the frame, so that the frame may be attached to the outside face of any window casing without fitting or otherwise adapting my invention for mounting on a window, except to slightly bevel the lower edge to fit the sill of the window casing.

The storm sashes and screens are the same size and are interchangeable, and no fitting is required to adapt them to the frame. Furthermore, very little hardware is required and my entire device may be made up and sold at relatively small cost and may be mounted on a window casing by an ordinary householder without the help of skilled labor, special tools or the like. Also the screen sashes and window sashes of my invention may be set up and removed with no effort and without help or tools.

Other important objects and advantages of my invention will be apparent as the detailed description proceeds with reference to the drawings, but it is to be understood that changes may be made in form, shape, size, proportion, construction and arrangement of parts without departing from my broad inventive concept, or what is claimed.

In the drawings wherein I have illustrated a preferred form of my invention:

Figure 1 is a front elevation of an ordinary window casing with my invention applied thereto; screens being shown in my frame;

Figure 2 is a section on the line 2—2 of Figure 1;

Figure 3 is a vertical section through a window casing and shows the detailed construction of my invention; glass sashes being substituted for screens to provide a storm window;

Figure 4 is a sectional detail of the rabbeted connection between a sash and a frame of my invention;

Figure 5 is a vertical elevation (from the inside) of my frame and sashes per se; screen sashes being used.

Figure 6 is a vertical section taken on the line 6—6 of Figure 5;

Figure 7 is a detail of the bolt adjustment for ventilation, and

Figure 8 is a detail of a plate spring for holding the upper sash in place.

5 In the drawings wherein like characters of reference are used to designate like or similar parts throughout the several views:

The numeral 1 designates ordinary frame building wall construction in which is an ordinary window casing 2 having upper and lower window sashes 3 and 4. The casing has a top 5, side rails 6 and a sill 7. All of the aforementioned parts are conventional and form no part of my present invention.

10 15 My invention embodies a rectangular flat frame 8 which is attached as at 9 to the outer flat face of the casing 2, with the lower edge resting on the sill 7—a drain opening 10 being left, if desired. It will be noted that no fitting is required to mount my frame, except slight beveling of the bottom edge to fit the sill.

20 25 My frame has a top and a bottom rail, 11 and 12 respectively, and side rails 13 the inner edges of which are rabbeted as at 14 to fit the rabbeted edges 15 of my screen or glass sashes 16. The upper and lower sashes of each frame are the same size and are interchangeable, and may be screen or glass depending on whether my invention is to be used as a storm window or screen, or

30 35 partly glassed and partly screened. Each sash (whether glass or screen) has rabbeted edges 15 fitting rabbeted edges 14 and top, bottom and side rails which lie flush with the top, bottom and side rails of the frame. The upper sash 11 has a rabbeted bottom edge fitting the rabbeted top edge of lower sash 18.

Upper sash 17 is held in place by spring plates 19 and a spring catch 20 so that the upper sash may be inserted or removed simply by tilting it and pulling it down. Spring plates 19 have parallel spaced heads 20 connected by a web part 21.

A pair of elongated triangular brackets 22 are attached as at 23 to each side of the lower sash 18 with the base upward, and each is provided with a row of openings 24 to receive slide bolts 25 carried by the lower sash to lock the lower sash in place, and in any one of several open positions for ventilation. Brackets 22 fit between the ordinary windows and my device. A catch plate or stop 26 may be provided at the bottom, if desired.

From the foregoing, it will be seen that all of the possibly available space between my storm windows and the ordinary windows is retained 55 so that a maximum insulating dead air space

is provided. It is believed that the operation and advantages of my invention will be apparent from the foregoing, but it is again emphasized that interpretation of my invention should only be made in the light of the subjoined claims.

What I claim is:

1. A combination storm window and screen, comprising a frame adapted to lie flat against the outside face of a window casing and be attached thereto with the bottom edge resting on the sill, interchangeable, similarly formed, shaped and proportioned sashes for the frame, said sashes and frame having inter-connected rabbeted edges and each sash having the inner and outer faces flush with the inner and outer faces of the frame, means for detachably connecting the sashes in the frame, wherein brackets are mounted on the frame on each lateral side of the lower sash, and means on the side portions of said sash adjustably engaging each bracket at a forward position thereon to tilt the sash with respect to the frame to provide ventilation.

2. The invention as described in claim 1 where-

in triangular brackets formed with spaced horizontally offset openings are respectively mounted on the frame to each side of the lower sash, and sliding catches are carried by said sash to engage in selected openings in the brackets to tiltably adjust the lower sash with reference to the frame to provide ventilation.

3. The invention as described in claim 1 wherein spring plates are carried by the frame to either side of the upper sash to support the upper sash, and said plates being flexible to permit tilting and removal of the upper sash from the frame.

4. The combination with a window casing and sill, of a frame attached to the outer face of the casing and resting on the sill, and interchangeable screens and window sashes of similar size, shape, and proportions detachably mounted in the frame to form either a storm window or screens, their inner and outer faces being flush with the frame, and means for detachably holding the same in the frame.

JOSEPH L. METZGER.
